(57) CLAIM

The ornamental design for a crown-styled clothing closure, as shown and described.

DESCRIPTION

FIG. 1 is a front perspective view of a crown-styled clothing closure showing my new design;

FIG. 2 is a front elevation view thereof;

FIG. 3 is a bottom plan view thereof;

FIG. 4 is a right side plan view thereof, the left side view being a mirror image;

FIG. 5 is a top plan view thereof; and,

FIG. 6 is the front elevation view of FIG. 2, now showing the crown-styled clothing closure in relation to a pocket.

The broken lines in FIGS. 1-6 are for illustrative purposes only to show an exemplary arrangement of jewels for the crown-styled clothing closure and to denote contours of one possible rear-facing surface. Likewise, the broken lines in FIG. 6 show an exemplary pocket but form no part of the claimed design.
